UNITED STATES PATENT OFFICE.

FREDERICK W. VINCENT, OF NEW YORK, N. Y.

HOISTING DEVICE.

SPECIFICATION forming part of Letters Patent No. 633,927, dated September 26, 1899.

Application filed March 4, 1899. Serial No. 707,724. (No model.)

To all whom it may concern:

Be it known that I, FREDERICK W. VINCENT, a citizen of the United States, residing at New York, in the county of New York and State of New York, have invented certain new and useful Improvements in Hoisting Devices, of which the following is a full and complete specification, such as will enable those skilled in the art to which it appertains to make and use the same.

This invention relates to hoisting devices such as are usually employed in hoisting coal-buckets, baskets, and other and similar receptacles; and the object thereof is to provide a device of this class having a swiveled hook adapted to engage with the bale of a bucket, basket, or similar receptacle and provided also with a swiveled connection for a guy-line, whereby the guy-line is prevented from becoming entangled with or being wrapped around the hook or its support.

The invention is fully disclosed in the following specification, of which the accompanying drawings form a part, in which—

25 Figure 1 is a sectional side view of the apparatus which I employ; Fig. 2, a plan view thereof; and Fig. 3, a view similar to Fig. 2, showing a modification, a part of the construction being in section.

30 In the drawings forming part of this specification the separate parts of my improvement are designated by the same numerals of reference in each of the views, and in the practice of my invention I provide a hook 5, which is swiveled in a circular collar or support 6, with the opposite sides of which are pivotally connected the sides of a yoke-shaped holder or support 7, which is provided with a shank 8, the upper end of which is provided with a ring 35 or eye 9, with which in practice the hoisting-cable 10 is connected.

The hook 5 is provided with a head 11 and is free to turn in the collar 6, and the said collar is free to swing in the yoke-shaped holder or support 7, and mounted on the shank 8 of the holder or support 7 is a collar 12, provided at one side with an extension 13, the top of which is provided with a longitudinal slot in which is pivoted, as shown at 14, an arm 15,

which is provided at its outer end with a ring 50 or eye 16, with which the guy-line 17 is connected.

The arm 15 is provided with a downwardly-directed projection 18, which holds it in a horizontal position; but said arm is free to swing vertically, and by means of this construction the support of the guy-line is free to turn on the yoke-shaped holder or support 7 and the said guy-line is prevented from becoming tangled or twisted around the holder 60 or support 7 or around the hook 5.

In the form of construction shown in Fig. 3 a pulley-wheel 19 is substituted for the eye or ring 16 in the end of the arm 15, and this form of construction is particularly adapted 65 for use where it is necessary to apply considerable power to the guy-line, and in this event the guy-line is fastened at one end and the other end is passed around the pulley-wheel 19 and may be connected with a windlass or 70 operated in any desired manner.

My improvement is simple in construction and operation and well adapted to accomplish the result for which it is intended and is also comparatively inexpensive.

Having fully described my invention, I claim as new and desire to secure by Letters Patent—

1. A hoisting device, comprising a yoke-shaped holder or support, a collar mounted 80 loosely therein, and a hook swiveled in said collar, said yoke-shaped holder or support being provided with a shank having an eye or ring, and a guy-line support swiveled on said shank, substantially as shown and described. 85

2. A hoisting device, comprising a yoke-shaped holder or support, a collar mounted loosely therein, a hook swiveled in said collar, said yoke-shaped holder or support being provided with a shank having an eye or ring at 90 the end thereof, and a collar swiveled on said shank and provided with a pivoted arm, substantially as shown and described.

3. A hoisting device, comprising a yoke-shaped holder or support, a collar mounted 95 loosely therein, a hook swiveled in said collar, said yoke-shaped holder or support being provided with a shank having an eye or ring at

the end thereof, and a collar swiveled on said shank and provided with a pivoted arm, said pivoted arm being adapted to be held in a horizontal position, and provided with means for connecting a guy-line therewith, substantially as shown and described.

5 In testimony that I claim the foregoing as

my invention I have signed my name, in presence of the subscribing witnesses, this 3d day of March, 1899.

FREDERICK W. VINCENT.
